UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

Application filed November 10, 1920. Serial No. 423,155.

To all whom it may concern:

Be it known that I, TALBOT G. MARTIN, a citizen of the United States of America, and a resident of Chicago, Cook County, and State of Illinois, have invented certain new and useful Improvements in Measured-Service Telephone Systems, of which the following is a specification.

The present invention relates in general to measured service telephone systems, and more particularly to automatic systems in which the subscribers' meters are located at the exchange. The object of the invention is to provide certain improvements in the meter control circuits, whereby a system of this kind is rendered more efficient in practice.

The improvements referred to will be described fully hereinafter with reference to the accompanying drawing, in which there is shown sufficient of the apparatus in an automatic telephone system to enable the invention to be explained and understood.

Referring to the drawing, the layout of the system shown therein is as follows: The telephone A, having the usual transmitter, receiver, bell, and calling device, is connected to the line conductors 2 and 3 in the usual manner. At the exchange the line terminates in the rotary line switch, indicated by reference character C, which is of well known construction and which is provided for the purpose of extending the line, responsive to the removal of the receiver at the telephone, to a trunk line terminating in an idle selector switch. One such trunk line, comprising conductors 41, 42, and 43, is shown extending to the selector D. Selector switches, as is well known, have the function of extending calling lines to idle connector switches in desired hundred groups, and there may be only one selector or a plurality in serial relation, in any given connection, depending on the size of the system.

As shown herein one of the trunk lines to which the selector D has access extends to the connector H, which is operable to complete connection to any one of a group of 100 lines, one of which is the line extending to the telephone station A'. Line, selector, and connector switches are well known in the art and, since they have nothing in particular to do with the invention, most of the circuit details have for simplicity been omitted.

The meters or call registers, such as the meter M associated with the station A, are located at any preferred place in the exchange as, for example, in a cabinet, or they may be mounted on the switchboard adjacent to the line switches. The meters are operated by relays in the selector trunks, such as relays 28, and 29, in a manner which will now be explained.

Suppose the subscriber at station A desires to call the subscriber at station A', in which case it will be necessary to actuate the meter M at the proper time to register the call. Upon the removal of the receiver at station A a circuit is completed over line conductors 2 and 3 for the line relay 5 of the line switch C. Upon energizing, the line relay 5 closes at its armature 7 a circuit which includes the switching relay 4 and the stepping magnet 6 in series, the circuit also extending through the meter M, individual to line switch C, to battery. The meter being marginally adjusted does not operate at this time. At the same time that the circuit of relay 4 is closed the line relay, by means of its armature 8, connects the test wiper 22 to the circuit at a point midway between the relay and the stepping magnet. The operation now depends upon whether the trunk line, with which the wipers of the line switch C are associated, is busy or is not busy. If the trunk line is busy the test contact with which the test wiper 22 is in engagement will be grounded, and as a result the switching relay 4 will be short circuited and the stepping magnet 6, being supplied with direct ground by way of the test wiper, will operate as a buzzer to advance the switch wipers step by step in search of an idle trunk line. It may be assumed, however, that when the call is initiated the wipers of the line switch C are standing upon the bank contacts shown in the drawing, and it may be assumed furthermore that the trunk line extending from these bank contacts is idle. Under these circumstances the test contact 25 will have no ground potential on it and when the receiver is removed the energization of line relay 5 is followed immediately by the energization of the switching relay 4. It may be stated at this point that the resistance of the switching relay 4 is very high so as to prevent the operation of the stepping magnet at this time. Relay 4, upon energiz-

110

ing, grounds the test wiper 22 at its armature 11, and at its armatures 9 and 10 disconnects the line conductors 2 and 3 from the winding of the line relay 5 and from ground, respectively, and extends them by way of wipers 21 and 23, bank contacts 24 and 26, and conductors 41 and 43 to the line relay (not shown) of the first selector D. When ground is placed upon test wiper 22 a circuit is closed for relay 28 by way of test contact 25, conductor 39, normally closed contact springs controlled by armature 33, conductor 38, armature 31 and its resting contact, and through the winding of relay 28 to battery. Upon energizing, relay 28 opens the shunt around the top winding of relay 29 at armature 35, prepares a circuit for the booster battery B at armature 34, and at armature 33 connects conductor 39 to the release trunk conductor 42 by way of the normally closed contact springs controlled by armature 32 of relay 29.

When the calling line is extended to the selector D as previously explained, the line and release relays of the selector are energized in the usual manner, and the latter relay connects ground to the release trunk conductor 42, thus establishing a holding circuit for relay 4 as follows: grounded release trunk conductor 42, normally closed contact springs controlled by armature 32, armature 33 and its working contact, conductor 39, test contact 25, test wiper 22, armature 11 and its working contact, winding of relay 4, and through the winding of magnet 6 to battery. The above described holding circuit is completed before the slow acting relay 5 has time to fall back, and it will be seen therefore that relay 4 will be maintained energized.

So far the circuits have been described in considerable detail in order to make the invention perfectly clear, but since the remainder of the equipment to be described in the connection is old, this will no longer be necessary. It will suffice to say that the subscriber at station A will now operate his calling device in accordance with the digits in the number assigned to station A', whereupon the selector D and a connector switch, assumed to be the connector H, are operated to complete the desired connection and signal the called subscriber.

Upon the removal of the called party's receiver the back bridge relay 59 of the connector is energized, this relay having the well known function of reversing the direction of current flow in the calling line. This brings us to the consideration of the means for actuating the meter M to register the call. The relay 29 in the trunk line extending to selector D is an electro-polarized relay, which has an inefficient polarizing winding of high resistance through which current flows from the grounded release trunk con-

ductor 42, while the trunk is in use. This winding and the top winding, which is in series with conductor 41, are in opposition during the establishment of the connection and until the called subscriber answers, relay 29 therefore remaining inoperative. When the called subscriber answers, and current is reversed in the calling line, the windings of relay 29 assist each other and the said relay is operated, with the result that armature 31 breaks the circuit of slow acting relay 28, while armature 32 operates to connect the booster battery B to the holding circuit at its working contact, at the same time disconnecting the release trunk conductor. A new circuit is thereby established for meter M as follows: ground at G, booster battery B, resistance R, working contact of armature 34 and the said armature, armature 32 and its working contact, armature 33 and its working contact, test contact 25, test wiper 22, armature 11 and its working contact, private normal conductor 1, and the winding of the operating magnet of meter M to battery. Since the booster battery B has its negative pole connected to ground, whereas the exchange battery has its positive pole connected to ground, the two will now assist each other. The meter magnet thereupon attracts its armature. A moment later the slow acting relay 28 releases; upon so doing it reconnects the release trunk conductor 42 to the holding circuit at the resting contact controlled by armature 33, and disconnects the booster battery by opening the working contact of the same armature. The booster battery is disconnected at armature 34 also, to guard against its being momentarily reconnected to the release trunk when armature 32 of relay 29 is released at the end of the connection. At armature 35 the top winding of relay 29 is short circuited so as not to interfere with the talking circuit. The armature of the magnet of meter M having been attracted when the booster battery was introduced into the circuit will be held energized by the exchange battery until the connection is released, which takes place, in the usual manner, when the receiver is replaced at station A, whereupon the armature is retracted to advance the number wheels to register the call.

The foregoing describes the usual operation in registering successful calls. It is understood, of course, that if the called line is busy, the connector in use will be prevented from completing the connection, and no call will be registered, and the same thing is true if the called subscriber fails to answer, for in neither case is the current reversed in the first selector trunk and relay 29 therefore is not operated.

Having described my invention, what I consider to be new and desire to have pro-

tected by Letters Patent will be pointed out in the appended claims.

What I claim as my invention is:

1. In a telephone system, a subscriber's line, a rotary line switch for extending said line when calling, said switch having two line wipers and a test wiper, a holding circuit for said switch including said test wiper, an individual meter for said line connected to said circuit, and means for momentarily increasing the current flow in said holding circuit to operate said meter, said means comprising a slow acting relay energized over said holding circuit, and a polar relay for opening the circuit of said slow relay.
  2. In a telephone system, a subscriber's line, a rotary line switch for extending said line when calling, said switch having two line wipers and a test wiper, a holding circuit for said switch including said test wiper, an individual meter for said line connected to said circuit, a booster battery, and means for connecting said battery in the holding circuit to operate said meter.
  3. In a telephone system, a calling subscriber's line, means including an individual line switch and a first selector switch for extending said line to a called line, a trunk line between the said line and selector switches, a holding circuit for the line switch including a third conductor of said trunk line, a meter connected to the holding circuit and responsive to normal current flow therein, and a polar relay in said trunk line for increasing the current flow in said holding circuit to operate said meter.
  4. In a telephone system, a calling subscriber's line, means including an individual line switch and a first selector switch for extending said line to a called line, a trunk line between the said line and selector switches, a holding circuit for the line switch including a third conductor of said trunk line, a meter connected to the holding circuit and responsive to normal current flow therein, and means in said trunk line operated when the called party answers to increase the current flow in said trunk line to operate said meter.
  5. In a telephone system, a calling subscriber's line, means including an individual line switch and a first selector switch for extending said line to a called line, a trunk line between the said line and selector switches, a holding circuit for the line switch including a third conductor of said trunk line, a meter connected to the holding circuit and responsive to normal current flow therein, a booster battery, and means in said trunk line
- for connecting said battery in said holding circuit to operate said meter.
6. In a telephone system, a calling subscriber's line, means including an individual line switch and a first selector switch for extending said line to a called line, a trunk line between the said line and selector switches, a holding circuit for the line switch including a third conductor of said trunk line, a meter connected to the holding circuit and responsive to normal current flow therein, a booster battery, and a relay in said trunk line operated when the called party answers to connect said battery in the holding circuit to operate said meter.
  7. In a telephone system, a calling subscriber's line, means including an individual line switch and a selector switch for extending said line to a called line, a trunk line between the said line and selector switches, a holding circuit for the line switch including a third conductor of said trunk line, a meter connected to the holding circuit and responsive to normal current flow therein, a final connector switch constituting part of said first means, means in said connector for reversing the direction of current flow in the line conductors of said trunk line when the called party answers, a booster battery, and a polar relay responsive to the said current reversal to connect said battery in the holding circuit to operate said meter.
  8. In a telephone system, a calling line, a meter for said line, a trunk line and a series of automatic switches for extending a connection from said line to a called line, a relay in said trunk line operated during the progress of the call to prepare an operating circuit for said meter, and a second relay operated when the call is answered to complete said meter circuit and to deenergize said first relay.
  9. In a telephone system, a line, a meter for said line, a trunk line, means including a series of automatic switches for extending connections from said line over said trunk line, a pair of relays normally connected to one conductor of said trunk line, one of said relays responsive during the progress of a call to cause a second winding of the other relay to be included in series with another conductor of said trunk line and to prepare an operating circuit for said meter, said other relay responsive when a call is answered to disconnect said first relay and to complete an operating circuit for said meter.

Signed by me at Chicago, Cook County, Illinois, this 28th day of Oct., 1920.

TALBOT G. MARTIN.
